A. A. MCRAE.

CUFF LINK.

APPLICATION FILED DEC. 3, 1919.

1,346,039.

Patented July 6, 1920.

UNITED STATES PATENT OFFICE.

ARTHUR A. MCRAE, OF ATTLEBORO, MASSACHUSETTS.

CUFF-LINK.

1,346,039.

Specification of Letters Patent.

Patented July 6, 1920.

Application filed December 3, 1919. Serial No. 342,212.

To all whom it may concern:

Be it known that I, ARTHUR A. MCRAE, a citizen of the United States, residing at Attleboro, in the county of Bristol, State of Massachusetts, have invented certain new and useful Improvements in Cuff-Links, of which the following is a specification.

My invention relates to improvements in cuff-links or cuff-buttons and consists particularly in a separable cuff-link having two opposite members adapted to be inserted through the buttonholes of the cuff and snapped into locking engagement with each other.

One object of the invention is to provide an improved snap-joint or clasping-means for the cuff-link whereby its parts are more securely fastened together against accidental separation, yet whereby they are adapted for easier and more convenient engagement and disengagement.

A particular object of the improvement is to provide a joint which will be more flexible to allow relative play between the parts of the cuff-link when they are fastened together, while also permitting the parts to tilt or rock so that they may yield when the cuff flexes without danger of their being pried apart.

The manner and means for carrying out the improvement are fully described in the following specification, illustrated by the accompanying drawings, in which like reference characters designate like parts. In the drawings:

Figure 1 is a side view of my improved cuff-link showing its parts separated;

Fig. 2, a view of the link showing the female member of its joint in section to illustrate the manner in which the male member engages therewith;

Fig. 3, a plan view of the female member of the joint, part sectional on the line X—X of Fig. 2 to show the spring-detent or locking-member thereof;

Fig. 4, a view showing the two parts of the link engaged and illustrating the manner in which they are allowed to play back and forth without becoming unclasped; and

Fig. 5, a part sectional view of the link showing how the parts may rock or tilt in relation to each other without being pried apart.

Referring first to Fig. 1, my improved

cuff-link comprises two coöperating members 2 and 3 having enlarged heads or buttons 4 which may be of any desired configuration and which are usually ornamented with engraved, chased, or enameled designs, 60 or set with precious or imitation stones, to give the required artistic effect. Projecting rearwardly from the back of the heads 4 are cylindrical shanks or posts 5 adapted for insertion through the buttonholes of the 65 cuff, and at the inner ends thereof are annular enlargements or flanges 6 for retaining the parts of the link in place in the buttonholes.

The two parts of the link are generally 70 constructed from hollow punchings, struck up in dies, and on the male member 3 is an elongated stud 7 projecting axially from the end of the post 5 to adapt it to enter a socket in the female member 2. The stud 7 is extended to a considerable distance from the end of the post 5 with its body 8 tapering slightly outwardly and terminating in a conical point 9.

Referring to Fig. 2, the female member 2 80 of the link is constructed with a convex face-plate 10 which is held by the swaged over edge 11 of a flat disk 12, these two parts forming the head 4 of the button as is the case with the opposite, male member 3. The 85 shank or post 5 of the member 2 is constructed from a cup-shaped shell which is flared outwardly at its end in a flange 14. The inner end of the post 5 is provided with a contracted neck 15 which passes through a 90 central opening in the disk 12 with its edge swaged over the rim thereof to unite the two parts with a permanent joint.

Set into the flaring end of the post 5 is a cylindrical socket-member 16 which is provided with an outwardly-flared flange 17 95 surrounded by a curled over rim 18. The socket-member 16 serves as a backing and retainer for a wire spring 20 which acts as the yielding-detent for the coupling or joint 100 between the two parts of the link. Referring particularly to Fig. 3, the spring 20 is formed with an arcuate portion 21, seated within the rim 18 of the socket-member 16, and provided with two parallel, spaced-105 apart legs 22 which engage the opposite side of the rim 18 at their ends. The legs 22 are joined to the arcuate portion 21 of the spring 20 by reversely bent loops 23, whereby to provide the necessary resiliency to 110

adapt the legs to spring apart when the stud 7 of the male member of the link is inserted between them.

Referring again to Fig. 2, the spring 20 is held in place in the socket-member 16 by means of a cap 24 having its outer rim swaged over the rim of the socket-member and the edge of the flange 14 on the post 5 to unite these latter parts together. The cap 24 is formed with a central opening or orifice 25 for receiving the stud 7 on the male member 3, and the face of the cap surrounding the opening is preferably concaved to provide an easy entrance for the stud.

Having now described the structure of my improved cuff-link in detail its method of operation will next be explained: The present type of cuff-link is intended for use particularly with double thickness cuffs of the so-called "French" style used on both ladies' and gentlemen's garments. The two members 2 and 3 are inserted separately through the double buttonholes in the opposite sides of the cuffs C, indicated by dash lines in Fig. 5, and are then fastened together in the following manner. One member is held by the finger and the other pushed against it, as with the thumb, to bring the stud 7 into register with the opening 25, see Fig. 2. A slight pressure of the fingers against the heads 4 will then cause the pointed end of the stud 7 to spread the legs 22 of the spring 20 apart to allow the stud to enter the socket in the member 2 as shown in Fig. 3. After the two parts of the link have been snapped together in this manner the pressure of the spring legs 22 against the sides of the tapered stud 7 will prevent their separation until they are forcibly pulled apart. The parts of the link may thus be easily united to hold the sides of the cuff together while being readily disconnected to unfasten the cuff. This type of link is much more convenient to fasten than where the parts of the button are connected by a hook and ring or snap-link arrangement, and the cuff is more readily released than with a permanently joined button where the head must be pushed through the buttonhole. It will therefore be seen that cuff-links of the present type are much more convenient and desirable than previous forms of buttons, since the wearer may easily unfasten his cuffs to roll up his sleeves. Likewise, on ladies' garments where the cuffs are too small to be slipped on over the hands they may be easily unfastened without removing the links from the buttonholes.

While my improved button is of this separable type to obtain the advantages above mentioned I do not rely upon this feature for novelty, as I am aware that separable, snap-jointed cuff-links are not new in the art. Heretofore this type of cuff-link has been open to serious objections, however, and

it is to avoid these objectionable features that the present improvement is provided. In previous types of separable links a ball-and-socket joint is employed for fastening the parts together and such a joint has not been found entirely practicable for this purpose. Considerable pressure is necessary to snap the ball into the socket, and to release the joint it requires a very strong pull or else a prying action on the opposite parts of the link. It has also been a common experience that when the cuff flexes, as in resting the wrist against an object, or under the active movement of the hands and arms, the ball-and-socket joint is very apt to be pried apart allowing the two members of the link to become released. One object of the present improvement is, therefore, to provide for an easier engagement and disengagement at the joint or coupling of the link while avoiding the danger of accidental separation of the parts; and a further and most important feature of the improvement is to adapt the parts of the button to rock or play under normal stresses without causing their disconnection.

Referring particularly to Figs. 2 and 3, it will be noted that the conical point on the stud 7 of the male member 3 of the link provides for a wedging action in forcing the sides of the spring 20 apart so that the stud may be very easily entered into its socket in the member 2. Only a very slight pressure is therefore required to snap the parts of the link together; and likewise, the tapered shank 8 of the stud acts as a wedge to provide for an easy release of the stud from its socket. It is to be particularly noted, however, that the shank of the stud 7 is elongated to a considerable degree and after it has been inserted into its socket it may slide back and forth therein to a considerable extent without releasing it from its detent or holding-means. It will also be observed from Figs. 4 and 5 that there is a considerable clearance space between the sides of the stud and the walls of the socket which surrounds it and this feature, taken in connection with the extreme length of the stud, provides for a rocking motion between the two parts of the link as graphically illustrated in Fig. 5. Stated briefly, the long stud and its enlarged socket provide for a maximum play between the two parts of the link when they are fastened together, so that they may give and take longitudinally as shown in Fig. 3, or may rock on a central pivot in the manner of a universal joint, as indicated in Fig. 5. This improved form of joint between the two members of the link therefore permits the parts to yield and give under the bending or flexing of the cuff, and also permits a swiveling action without causing its members to fly apart when the link strikes

against any object. My improved cuff-link is therefore much more securely held in the cuffs without danger of accidental unclasping of its parts, while also being easier and 5 more convenient to fasten and unfasten when required.

My improvement depends on certain features of construction and arrangement which provide for a flexible joint between 10 the parts of the link as set forth in the following specification, and what I claim as novel and wish to secure by Letters Patent of the United States is:

1. In a separable cuff-link, the combination with a button-member having a post for insertion through the buttonhole of the cuff and a tapered stud projecting therefrom said stud having an extended neck of a length several times its diameter with a 20 conical point at its end, of a second button-member having a post provided with an enlarged socket at its end adapted to receive the stud on the first member with a clearance around its sides, and a spring-detent 25 in the socket adapted to clasp the tapered sides of the stud to hold the parts of the link together while allowing them to play back and forth to a considerable extent and to rock laterally in relation to each other 30 without becoming unclasped.

2. In a separable cuff-link, the combination with a button-member having a flanged post for insertion through the buttonhole of the cuff and an elongated prong-like stud 35 formed with an elongated neck and a tapered enlargement at its end, of a second

button-member having a flanged post provided with a central socket of greater diameter than that of the stud to adapt it to receive the latter with a clearance around its 40 sides, and a detent provided with spaced-apart spring-members projecting across the entrance to the socket to adapt them to clasp the sides of the post while allowing it to play back and forth in the socket to a considerable extent to permit the two members to rock and tilt in relation to each other without becoming unclasped.

3. In a separable cuff-link, the combination with a button-member formed with a 50 head having a hollow cylindrical post attached thereto and provided with an elongated tapered stud projecting therefrom with a conical enlargement at its end, of a second button-member formed with a head 55 and a hollow cylindrical post flanged outwardly at its end, a cuplike socket-member held within the post and provided with a flange at its end surrounded by an annular rim, an arcuate spring seated within the 60 rim of the flange on the socket-member and provided with parallel spaced-apart legs extending across the socket, and a cap fitted across the end of the socket-member with its rim swaged over the edge of the flange on 65 the post to secure the parts together, said cap provided with a central orifice to allow the post on the first member to be inserted into the socket to be clasped by the legs of the spring.

In testimony whereof I affix my signature.
ARTHUR A. McRAE.
